(57) **CLAIM**

We claim the ornamental design for a grease wall bracket system, as shown and described.

DESCRIPTION

FIG. 1 is a perspective view of a grease wall bracket system with broken line grease containers hanging on the bracket showing our design;

FIG. 2 is a front elevation view thereof;

FIG. 3 is a rear elevation view thereof;

FIG. 4 is a left side elevation thereof;

FIG. 5 is a right side elevation thereof;

FIG. 6 is a top plan view thereof; and,

FIG. 7 is a bottom plan view thereof.

Features shown in broken lines in the drawings are not part of the claim.
